Patented Nov. 19, 1968

212,788

CLIP FOR A WRITING INSTRUMENT OR THE LIKE

Ludwig F. Perwas, Mountainview Ave.,
Orangeburg, N.Y. 10962

Filed Dec. 18, 1967, Ser. No. 9,838

Term of patent 14 years

(Cl. D74—2)

Fig. 1

Fig. 2

Fig. 4

Fig. 3

Fig. 5

Fig. 6

Fig. 7

Fig. 8

Fig. 9

FIGURE 1 is a perspective view of a clip for a writing instrument or the like showing my new design;

FIGURE 2 is a lateral view;

FIGURE 3 is an opposite view of FIGURE 2;

FIGURE 4 is a top view;

FIGURE 5 is a rear view thereof;

FIGURE 6 is a front view of another embodiment of the clip for a writing instrument or the like shown in FIG. 1 wherein the fastening stud is of less width and is attached to the shank of the clip;

FIGURE 7 is a lateral view of FIGURE 6;

FIGURE 8 is a top view; and

FIGURE 9 is a rear view thereof.

I claim:

The ornamental design for a clip for a writing instrument or the like, as shown and described.
